FOLDING HANDLE

Warren H. West, Seabrook Beach, N.H., assignor to Cambridge Thermionic Corporation, Cambridge, Mass., a corporation of Massachusetts

Filed June 1, 1960, Ser. No. 33,265

5 Claims. (Cl. 16—126)

The field of this invention is that of handles, and the invention relates, more particularly, to handles which can be moved into several positions.

Objects of this invention are to provide a folding handle assembly which is especially suitable for use with structures for mounting electrical equipment, such as panels or chassis or components thereof; to provide such a handle that can be conventionally rotated between an inoperative position laying flat against a surface of the said structure, and an operative position laterally extending therefrom, the handle being securely retained in either of said positions and incapable of being rotated beyond the extending position so that the structure can be conveniently and securely moved by means of the handle; to provide such a handle which will occupy a minimum of space in inoperative position; and to provide a handle assembly which is exceptionally strong, pleasing of appearance and reliable in operation and which, nevertheless, can be simply and inexpensively manufactured, assembled and mounted.

The substance of the invention can be briefly summarized as follows.

In one of its principal aspects, the handle assembly according to the invention comprises body or mounting means which are attachable to a supporting structure to be manipulated by the handle, and which mounting means have socket means therein, key means disposed within these body socket means, and means for normally biasing the key means to extend from the socket means; a handle piece having a series of locking elements pivotally mounted on the body means so that the locking elements are successively and releasably engaged with the key means as the handle is pivoted into respective positions, thereby automatically and detachably to hold the handle in any of such positions.

In a preferred embodiment of the invention the above body or mounting means comprise a pair of threaded studs each having a slotted end and a blind axial bore in the base of its end slot. A coil spring and a key pin are disposed in each of these axial stud bores such that the spring serves to bias the pin normally to extend from the stud bore. A U-shaped handle piece adapted to pivot about an axis extending through the ends of the handle is pivotally mounted in the slots of the threaded studs and is provided with a pair of notches in each end which are circumferentially spaced around the handle axis and which are separated by an arcuate surface concentric with the axis. The handle notches are spaced and the handle is pivotally mounted adjacent to the key pins so that when the handle is laying flat against the article to which the mounting studs are attached, the pins engage one notch on each end of the handle; when the handle is pivoted to a position where it extends horizontally from the article, the pins engage the other notches in the handle ends. In this manner the handle can be detachably held in either of the handle positions but can be moved to the other of said handle positions by application of a force sufficient to wedge the pins into their respective bores against the bias of their respective springs.

In the above characterized preferred embodiment of this invention, the handle ends are provided with shoulder means engageable with the bases of the stud slots in the extending handle position so that the handle will not

2

rotate beyond extended position and can be used for lifting the article to which the handle is attached. In an alternative embodiment, the stud slots are provided with shoulder means which engage the handle in extended position wherein it can be used for similar lifting purposes.

Other objects, inventive aspects, advantages and details of preferred construction will appear from the following description of two typical practical embodiments illustrating the novel characteristics of the invention.

The description refers to a drawing in which

FIG. 1 is a plan view of the handle assembly according to this invention, showing the handle piece in extended position;

15 FIG. 2 is a sectional view along line 2—2 of FIG. 1;

FIG. 3 is an enlarged side elevation view of the handle assembly showing the handle piece laying flat against the structure to which the handle is attached;

20 FIG. 4 is a sectional view of FIG. 3, taken on the same plane as FIG. 2; and

FIG. 5 is a sectional view similar to FIG. 2 showing an alternative embodiment of the handle assembly according to this invention.

In the drawing, numeral 2 indicates the handle assembly proper as provided by the invention. This assembly is shown as mounted upon an article such as a drawer, chassis, or instrument panel compartment, such a supporting structure being diagrammatically represented in dot and dash lines at 4.

30 The handle assembly 2 includes body or mounting means such as a pair of threaded studs 6, 7 for attaching the assembly to the article 4, each stud having an axial end slot 8 forming the slot side walls 9, 10 and the slot base surface 12. Each stud also has a blind axial bore 35 14 (FIG. 2) in the base 12 of its end slot. The studs can be secured to the supporting article in conventional manner either by engaging a nut (not shown) with the thread on the ends of the studs 6, 7, or by engaging each stud thread in a corresponding threaded bore in the article such as indicated at 4.1. In this latter instance, the stud end slots will accommodate a screw driver or other turning means for rotating the studs into threaded engagement with the article bores. Preferably each stud is provided with a head portion 6.1, 7.1 forming a shoulder 6.2, 7.2

40 by means of which the stud can be conveniently positioned on the article so that, when the end slots of the studs are in parallel relation, the bases 12 of the slots will be aligned flush with each other.

45 A pin 16 (FIG. 2) preferably having a wedge-shaped end 16.1 is fitted within the axial bore of each stud and adapted to be axially slidable therein. A coil spring 18 is disposed within each of the bores for biasing the pins normally to extend from the bores. The pins can be made of any relatively hard, smooth material but the hard and slippery material called Teflon has proved most suited for this purpose.

50 The handle assembly further includes a U-shaped handle piece 20 which has arms 22, 23 of equal length—60 which has handle piece ends 24, 25 reduced as at 24.1, 25.1 where necessary, adapted to be accommodated in respective stud end slots 8—and which has coaxial bores 26 in the handle piece ends defining an axis 28 about which the handle piece is adapted to rotate. The side walls 9, 10 of the stud end slots are coaxially bored, as 65 at 10.1 (FIG. 3), to match the handle piece bores 26, and rolled or spring pins 30 are fitted within respective sets of said bores for pivotally mounting the handle piece in the stud slots for rotation about the handle axis 28.

70 Each handle end is provided with a pair of notches 32 and 34 which are circumferentially spaced about the axis 28 and which are separated by an arcuate surface 36 concentric with that axis. The handle axis is located and

the handle notches are spaced so that the handle piece can be rotated about this axis between an inoperative position laying flat against the surface of the article to which the handle assembly is attached, as shown in FIG. 3, and a position extending from the article, as shown in FIG. 2. The notch 32 on each handle end is adapted to receive the wedge-shaped end of its respective pin 16, as biased by a spring 18, when the handle piece is in extending position, and the notch 34 on each end of the handle is adapted to receive the said pin when the handle is in inoperative position. The handle piece will be detachably held in either position by engagement of the pins in the respective notches. However, when the handle piece is forcibly rotated from one position to the other, the arcuate surface 36 separating each pair of handle notches will ride over its respective pin 16 wedging it within its respective bore against the bias of the spring 18.

Each handle end is provided with a shoulder 38 (FIG. 2) which tangentially extends from the notch 32 oppositely of the above described arcuate surface 36 and which is adapted to abut the base 12 of its respective stud slot 8 when the handle is in extending position. This prevents rotation of the handle piece beyond that extending position and permits use of the handle for lifting the article in the general direction of the base 12, that is at right angles to the plane of the extended handle. A surface 40 on each arm 22, 23 of the handle piece tangentially extends from the notch 34 oppositely of the arcuate surface 36, and, corresponding to the shoulder 38, is adapted to abut the base 12 of its respective stud slot 8 when the handle is in inoperative position.

As shown in FIG. 2, when the handle piece is in inoperative position abutting the bases 12 of the mounting stud slots, the handle is preferably spaced a very short distance from the handle mounting surface of the article 4, thereby to assure that the handle piece is detachably engaged by the key pins 16 so that the handle will not rattle against the article, and thereby to facilitate subsequent gripping of the handle for rotating the handle to extended position. However, where space is at a premium, the bases 12 of the stud slots can be made flush with the handle mounting surface of the article 4. Preferably also the heads 6.1, 7.1 of the handle mounting studs are adapted to be flush with the outer surfaces of the handle piece when the handle piece is in inoperative position so that the handle assembly will occupy the minimum of mounting space.

It can thus be seen that the handle assembly provided by this invention is of light, simple and inexpensive construction nevertheless providing extremely certain and secure operation, that this assembly can be rotated between two precisely definite handle positions, can be detachably held in either handle position, and will abut a fixed surface as it is detachably held in each of said positions. Thus the handle in extended position can be used to pull, lift or push the article to which it is attached, and will conveniently remain in extending position until forcibly returned to inoperative position. In inoperative position, the handle occupies a minimum of space and will not rattle in response to movement or vibration of the article to which it is attached.

In FIG. 5, an alternative embodiment of the handle assembly is illustrated. In this construction, the U-shaped handle 120 is adapted to pivot about an axis 128 as above-described, but each handle piece end 124 is finished with a semicylindrical surface 136 centered on the axis and with a pair of notches, 132 and 134 respectively, which are circumferentially spaced on this surface. Each mounting stud 106 has a slot 108 in one end, with slot side walls 110—110, with a slot base 112, and with a slot end shoulder 113.

In this construction, when the handle is rotated to a position horizontally extending from an article as above described, the notch 132 in each handle end will be detachably engaged with a key pin 116. A surface 138 on

each handle piece arm 122 will then abut a respective slot shoulder 113 for preventing rotation of the handle beyond the extending position and permitting use of the handle for lifting the structure to which the handle assembly is attached. When the handle assembly is rotated to an inoperative position, a surface 140 in each handle piece arm abuts the base 112 of its respective stud slot as above described.

It should be understood that the present disclosure is for the purpose of illustration only and that this invention includes all modifications and equivalents which fall within the scope of the appended claims.

I claim:

1. A handle assembly comprising: a U-shaped handle piece adapted to pivot between two handle positions around an axis extending through the ends of said handle piece, each of said ends having a pair of notches circumferentially spaced around said axis and separated by an arcuate surface centered on said axis, each of said ends having a shoulder tangentially extending from each of said notches oppositely of said arcuate surface; body means attachable to a supporting structure, said body means having slots for receiving respective handle piece ends and having a blind bore in the base of each slot; a pin axially slidable within each of said bores; spring means for biasing said pins to extend from said bores; and means for pivotally mounting the handle piece ends in their respective slots for rotation about said handle axis; whereby, as the handle piece is rotated into each handle position, said pins will engage respective notches in each end of the piece for detachably holding the piece in said position, and a shoulder on each end of the piece will engage the base of its mounting slot for positively limiting rotation of the handle piece.

2. A handle assembly comprising: a U-shaped handle piece adapted to pivot between two handle positions about an axis extending through the ends of said handle piece, each of said ends having a pair of notches circumferentially spaced around said axis and separated by an arcuate surface concentric with said axis, and each of said ends having a shoulder extending from each of said notches tangentially to said arcuate surface; a pair of threaded studs attachable to a supporting structure, said studs each having an axially slotted end for receiving respective handle piece ends and having a blind axial bore in the base of said slot; a pin axially slidable in each of said bores; a coil spring disposed in each of said bores for biasing said pins to extend from said bores; and means for pivotally mounting the handle piece ends in their respective slots for rotation about said handle axis; whereby, as the handle piece is rotated into each handle position, said pins will engage respective notches in each end of the piece for detachably holding the piece in said position, and a shoulder on each end of the piece will engage the base of its mounting slot for positively limiting rotation of the handle piece.

3. A handle assembly comprising: a U-shaped handle piece adapted to pivot between two handle positions about an axis extending through the ends of said handle piece, each of said ends having an arcuate surface centered on said axis, a pair of notches circumferentially spaced along said arcuate surface, one notch in the plane of said handle piece and the other at right angles thereto, and a flat surface tangentially extending from said first notch at right angles to said handle plane; body means having stud means for attaching it to a supporting structure, having slots for receiving respective handle piece ends, each of said slots with two side walls and a bottom wall transverse to said stud means, and having a blind bore in the base thereof; a pin axially slidable within each of said bores; spring means for biasing said pins to extend from said bores; and means for pivotally mounting the handle piece ends in their respective slots for rotation about said handle axis; whereby, as the handle is rotated into each handle position, said pins will engage respec-

tive notches in each end of the handle piece for deattachably holding the piece in said position, and handle piece rotation beyond said positions is limited by the slot bottom wall and flat handle end surface respectively.

4. A handle assembly including a handle piece and a receiving assembly therefor,

said receiving assembly being attachable to the face of a supporting structure and comprising a stud having a head, an axial slot formed in said head and defined by a base and opposed sides thereof, 10 an axial bore formed in the base of said slot and a pin axially slidible in said bore, said pin being spring biased to a normal position extending from said bore; and

said handle piece having an end portion pivotally mounted in said slot for rotational movement between two handle positions about an axis extending through the end of said handle piece, one of said handle piece positions being retracted and generally flush with the face of the supporting structure while 20 the other position is extended and inclined to the face of the supporting structure, said end portion including an arcuate surface centered on said axis and a pair of notches circumferentially spaced along said arcuate surface, one notch in the plane of said 25 handle piece and the other disposed at an angle thereto, and a shoulder having a flat face projecting beyond said arcuate surface, the flat face of said projecting shoulder being engageable with said base of said axial slot of the receiving assembly thus 30 forming a positive stop for the extended position of the handle piece.

5. A handle assembly including a U-shaped handle piece and a receiving assembly therefor, 35 said receiving assembly being attachable to the face of

a supporting structure and comprising a pair of studs each having a head, an axial slot formed in each of said heads and defined by a base and opposed sides thereof, an axial bore formed in the base of said slots and a pin axially slidible in each of said bores, said pins being spring biased to a normal position extending from said bores; and said handle piece having end portions pivotally mounted in said slots for rotational movement between two handle positions about an axis extending through said ends of said handle piece, one of said handle piece positions being retracted and generally flush with the face of the supporting structure while the other position is extended and inclined to the face of the supporting structure, each of said end portions including an arcuate surface centered on said axis and a pair of notches circumferentially spaced along said arcuate surface, one notch in the plane of said handle piece and the other disposed at an angle thereto, and a shoulder having a flat face projecting beyond said arcuate surface, the flat face of said projecting shoulder being engageable with said base of said axial slot of the receiving assembly thus forming a positive stop for the extended position of the handle piece.
